DESIGN FOR A CLOTHESPIN

Virginia J. Jacobsen, San Diego, Calif.

Application January 10, 1948, Serial No. 143,645

Term of patent 7 years

(Cl. D17—6)

To all whom it may concern:

Be it known that I, Virginia J. Jacobsen, a citizen of the United States of America, residing at San Diego, in the county of San Diego and State of California, have invented a new, original and ornamental Design for Clothespin, of which the following is a specification, reference being had to the accompanying drawing, forming a part thereof.

The figure of the drawing is a perspective view of a clothespin, showing my new design.

I claim:

The ornamental design for a clothespin, substantially as shown.

VIRGINIA J. JACOBSEN.
